UNITED STATES PATENT OFFICE.

WILLIAM JAMES FOSTER AND HENRY LOCKWOOD FOSTER, OF ARLINGTON COUNTY, VIRGINIA.

DESIGN FOR A BIRD HOUSE.

Application filed August 31, 1922. Serial No. 3,610. Term of patent 14 years.

To all whom it may concern:

Be it known that we, WILLIAM JAMES FOSTER and HENRY LOCKWOOD FOSTER, citizens of the United States, residing at Arlington County, Va., have invented a new, original, and ornamental Design for Bird Houses, of which the following is a specification, reference being had to the accompanying drawing, forming part thereof.

What we claim:

The ornamental design for a bird house, as shown.

WILLIAM JAMES FOSTER.
HENRY LOCKWOOD FOSTER.
